Primary Examiner — Cynthia Ramirez*Assistant Examiner* — Michael Maharajh(74) Attorney, Agent, or Firm — Daniel Boudwin; Global Intellectual Property Agency, LLC(57) CLAIM

The ornamental design for a composter, as shown and described.

DESCRIPTION

FIG. 1 shows a perspective view of a composter showing my new design;

FIG. 2 shows a front perspective view wherein the lid is open;

FIG. 3 shows a front view thereof;

FIG. 4 shows a rear view thereof;

FIG. 5 shows a right side view thereof;

FIG. 6 shows a left side view thereof;

FIG. 7 shows a top plan view thereof;

FIG. 8 shows a bottom plan view thereof;

FIG. 9 shows a perspective view of another embodiment of a composter showing my new design;

FIG. 10 shows a perspective view wherein the lid is open;

FIG. 11 shows a front view thereof;

FIG. 12 shows a rear view thereof;

FIG. 13 shows a right side view thereof;

FIG. 14 shows a left side view thereof;

FIG. 15 shows a top plan view thereof; and,

FIG. 16 shows a bottom plan view thereof.

The broken lines shown in the Figures show portions of the composter which form no part of the claimed design.
